2,451,113

AUTOMATICALLY ADJUSTABLE LADDER

Karlis V. Ozols, Brooklyn, N. Y.

Application August 9, 1945, Serial No. 609,751

6 Claims. (Cl. 228—63)

1

The invention relates to ladders and particularly to step ladders to be positioned on uneven or inclined localities or bases.

To solve this problem various devices have been suggested mostly based on the use of vertically displaceable compensating and extension members, the displacement of these extensions being frequently effected by the cooperation of racks fastened to the ladder and pinion wheels provided on the ladder legs.

It is the primary object of the invention to render the adjustment of the ladder legs by means of extension members and the positioning of the ladder on uneven localities and bases automatically operative.

It is another object of the invention to effect the automatic compensation of uneven localities upon which the two ladder legs rest by the weight of the ladder legs.

It is also an object of the invention to automatically secure the ladder in the level compensating position.

It is another object of the invention to provide a ladder which upon being lowered from any point onto uneven locality will automatically assume and retain the position in which it may be stationed and will be secured in the same.

A further object of the invention is to provide a step ladder which in addition to the above described advantages will be efficient, durable, inexpensive in manufacture and at the same time simple in construction and operation.

With these objects in view the invention will now be described in detail and with reference to the accompanying drawings, in which identical elements are denominated with the same numerals.

In the drawings,

Fig. 1 is a fragmentary vertical side elevation of one ladder leg,

Fig. 2 is a vertical fragmentary side elevation of the other ladder leg,

Fig. 3 is a fragmentary vertical front elevation of the ladder, the leg ends being shown in section on line 1—1 and 2—2 of Figs. 1 and 2,

Fig. 4 is on an enlarged scale a horizontal section on line 3—3 of Fig. 3.

Referring more particularly to the drawing, 1 and 2 denote the lower ends of the two ladder legs, which are connected by rungs 3.

2

Leg 1 is provided with a distance compensating member 5; this member 5 is in the present embodiment of the invention shown to partly encircle ladder leg 1, and is made vertically displaceable in relation to the latter.

Member 5 is provided with two outwardly projecting vertically extending edges 29, 30 whose inner faces are shaped to form racks 6 and 10 having teeth of equal pitch. The operating face 10 of rack 6 is wider than that of rack 10, as apparent from Fig. 4.

A horizontal shaft 8 is mounted by means of sleeves 31 in the ladder legs; that part of the shaft passing through leg 1 is enlarged to form a square shaped head 15; the square shaped enlargement 15 prevents shaft 8 from rotating within the ladder legs, but does not prevent its horizontal displacement or reciprocation on slide bearings 31.

20 The one end of shaft 8 outwardly projecting from ladder leg 1 carries a pinion wheel 7 which is loosely rotatable thereon, but may be prevented from being displaced in axial direction on or in relation to shaft 8; in other words, wheel 7 cannot move in axial direction independently of shaft 8, but it is displaced when the shaft is reciprocated in the axial direction.

Shaft 8 is normally so located in legs 1, 2 that 30 pinion wheel 7 is in constant meshing engagement with the outer portion of the wider rack 6; therefore, the distance compensating member 5 can freely reciprocate in vertical direction, the pinion wheel 7 rolling along in coaction with rack 6. If, however, shaft 8 is displaced in the direction of arrow S, pinion wheel 7 engages the opposite rack 10 which will result in a stoppage of the hitherto free displacement of extension member 5 and immobilize the same in the corresponding position.

A slot 9 is provided in the distance compensating member 5, the upper and the lower end of the slot to be used for limiting the reciprocation of member 5 in its vertical direction.

45 A hollow extension 12 is inserted in the lower end of distance compensating member 5; the latter is rendered vertically displaceable in relation to extension 12 by means of bolt 33 mounted in member 5 and slot 13 provided in extension 12. 50 Extension 12 is supported in member 5 on spring

14, which is inserted between bolt 33 and the bottom 21 of extension 12.

Shaft 8 is, at the end opposite the distance compensating member 5, provided with a threaded portion 20; the latter cooperates with pinion wheel 19 secured on the threaded shaft portion 20. This pinion wheel 19 is provided with teeth on its periphery meshing with rack 18 of rod 17. The lower end of ladder leg 2 is reciprocally inserted into a hollow extension 16 and supported on spring 22 located in the latter.

A rod 17 extending alongside the lower end of leg 2 is connected with extension 16; this rod carries at its upper end rack 18 which, as mentioned above, meshes with the toothed circumference of pinion wheel 19, the latter meshing with the threaded portion 20 of shaft 8.

The operation of the ladder is as follows:

It may for demonstrative purposes be assumed that the ladder is to be positioned on an inclined locality in such a manner that leg 1 will have to rest on a lower level than leg 2.

The ladder is set on this locality. The distance compensating member 5 will slide down by gravity over leg 1 from a normally secured position, whereby the larger rack 6 freely passes along rotating pinion wheel 7; the latter does not mesh with rack 10 during this initial stage of the ladder adjustment. When compensating member 5 reaches the lower level point, its weight partially compresses spring 14 and extension 12 moves for the same distance into the compensating member.

Now the ladder legs move down along compensating member 5 until extension 16 strikes the ground. The weight of the ladder compresses spring 22 and leg 2 moves down accordingly; consequently pinion wheel 19 is set in rotation by engagement with rack 18 of rod 17 supported on the ground; by the rotation of wheel 19 the threaded portion 20 of shaft 8 is accordingly rotated; shaft 8 is displaced in the direction of arrow S and pinion wheel 7 is now moved in coaction with rack 10; at this moment pinion wheel 7 is engaged by both racks and its further rotation is stopped.

During the last stage of the operation rack 18 continues to rotate pinion wheel 19 on the threaded end of shaft 8; accordingly pinion 7 is completely moved between racks 6 and 10, whereby the ladder is automatically locked in the operating position.

I claim:

1. A ladder for use on an uneven locality comprising an extension foot attached to the one ladder leg, said foot being freely displaceable along said ladder leg, a shaft transversally shiftable in the two ladder legs, a pinion wheel rotatably carried by the one end of said shaft, parallel racks of different width carried by said extension foot to be successively brought in meshing cooperation with said pinion wheel, means connected with the other ladder leg to displace said shaft and said pinion wheel upon arrival of the ladder in its operating position and to thereby effect the meshing cooperation of said pinion wheel with both of said racks to thereby stop the free displacement of said extension foot and to lock the same in the thus adjusted position.

2. A ladder for use on an uneven locality comprising a distance compensating member movably attached to one ladder leg and lowerable by gravity along the same, an extension resiliently connected with the lower end of the second ladder leg, said leg adapted to be moved downwardly towards said extension by the weight of

the ladder upon its location in the operative position, means operative upon the downward movement of said leg to automatically stop the displacement of said compensating member and to lock the same and the first ladder leg in the thus adjusted position.

3. A ladder for use on an uneven locality comprising a distance compensating member movably attached to one ladder leg and lowerable by gravity along the same, an extension sleeve closed at its lower end and accommodating the lower end of the second ladder leg, a spring between said closed sleeve end and the lower end of said leg adapted to be compressed by the weight of the ladder upon its location on the operative position and to lower said ladder leg into the sleeve, means operative upon the downward movement of said leg to automatically stop the displacement of said compensating member and to lock the same and the first ladder leg in the thus adjusted position.

4. A two-leg ladder for use on an uneven locality comprising a distance compensating member movably attached to one ladder leg and lowerable by gravity along the same, a shaft transversally shiftable in both ladder legs, a pinion wheel rotatably carried by the one end of said shaft, parallel racks of different width carried by said compensating member, means to successively bring said racks in meshing cooperation with said pinion wheel, said means including a second pinion wheel carried by the other end of said shaft, means connected with the second ladder leg operative upon the weight of the ladder to rotate said pinion wheel and to transversally displace said shaft upon arrival of said leg in the operative position of the ladder whereby said first pinion wheel carried on said shaft is moved into meshing cooperation with both racks to stop further displacement of said compensating member and said first leg and to lock the same in the thus adjusted position.

5. A two-leg ladder for use on an uneven locality comprising a distance compensating member movably attached to the one ladder leg and lowerable by gravity along the same, a shaft transversally shiftable in both ladder legs, the portion of said shaft located in the compensation member carrying leg being enlarged to form a square-shaped head preventing rotation of said shaft but permitting its transversal movement, a pinion wheel rotatably carried by the one end of said shaft, parallel racks of different width carried by said compensating member, means to successively bring said racks in meshing cooperation with said pinion wheel, said means including a second pinion wheel carried by the other end of said shaft, means connected with the second leg operative upon the weight of the ladder to rotate said pinion wheel and to transversally move said shaft upon arrival of said leg in the operating position of the ladder, whereby said first pinion wheel carried by the shaft is moved into meshing cooperation with both racks to stop further displacement of said compensating member and said first leg and to lock the same in the thus adjusted position.

6. A two-leg ladder for use on an uneven locality comprising a distance compensating member movably attached to the one ladder leg and lowerable by gravity along the same, a shaft transversally shiftable in both ladder legs, a pinion wheel rotatably carried by the one end of said shaft, parallel racks of different width carried by

said compensating member, means to be successively brought in meshing cooperation with said pinion wheel, a second pinion wheel carried by the other end of said shaft, an extension resiliently connected with the lower end of the second ladder leg, a rack attached to said extension in meshing engagement with said second pinion wheel adapted to rotate the latter and to displace said shaft transversally upon arrival of said leg in the operating position of the ladder, whereby said first pinion wheel carried by the shaft is moved into meshing cooperation with both racks to stop further displacement of said

5 compensating member and said first leg and to lock the same in the thus adjusted position.
